SWITCH OPERATING MECHANISM

Sigurd I. Lindell, Chicago, Ill., assignor to S. & C. Electric Company, Chicago, Ill., a corporation of Delaware

Application November 14, 1950, Serial No. 195,610

9 Claims. (CL 200—48)

1

This invention relates, generally, to mechanisms for operating high voltage electric power switches and it has particular relation to mechanisms for operating switches of the general character disclosed in the copending application of Lindell, Serial No. 41,597, filed June 30, 1948, and of Kojis, Serial No. 158,246, filed April 26, 1950, now Patent No. 2,613,291, issued October 7, 1952, both assigned to the assignee of this application.

These switches usually are assembled in units of three for gang operation on a three phase circuit. Each switch unit includes a base on which are mounted three insulators. The central insulator is rotatable and carries a switch blade for engagement at either end with main switch contacts that are supported on the outlying insulators on the base. In order to avoid arcing on opening or closing of the main contacts, each of the outlying insulators also carries a load interrupter to which the current flowing through the main contacts is transferred prior to opening thereof. The load interrupter is designed to quickly and efficiently interrupt the arc which is formed on separation of its contacts and for quickly closing the circuit when its contacts are closed.

Preferably the main contacts are designed and constructed so that they engage under relatively high pressure. The purpose of this is to minimize losses incident to current flow through the main switch contacts. In order to disengage or engage the main switch contacts a relatively great force must be applied to the switch blade. However, this force need be applied only during a relatively small portion of the full movement of the switch blade from or to switch closed position.

The load interrupter on each of the outlying insulators is operated by the switch blade in its movement from or to the switch closed position. It is desirable that its contacts be separated at a relatively high speed for the purpose of effecting a corresponding rapid extinction of the arc drawn therebetween.

From the foregoing it will be apparent that the movement of the switch blade from and to the switch closed position where the main contacts are disengaged and engaged, a relatively great force must be applied during a relatively small portion of the total travel of the switch blade. Also it will be apparent that the movement of the switch blade must be accelerated rapidly in order to effect the desired high speed operation of the load interrupter for opening or closing the circuit therethrough.

2

Accordingly, among the objects of this invention are: To provide for operating each switch unit and for operating them in unison in a simple, efficient and economical manner; to interconnect driving means and the blade of each switch unit in such manner as to operate the switch blade with sufficient force to disengage and engage the main switch contacts during a relatively small movement of the switch blade and to accelerate the movement of the switch blade relative to the driving means while the former is operating the load interrupter; to employ a toggle linkage for accomplishing these functions; to arrange the toggle linkage so that the links thereof are in about end-to-end centered relation when the associated switch is closed; to limit the movement of the toggle linkage slightly past the center position so as to lock the switch blade individual thereto in the switch closed position; to pivot one of the links of the toggle linkage on the base carrying the insulators on which the switch blade and switch contact are mounted; to apply a turning moment to this one link for operating the corresponding switch blade from and to the switch closed position; and to apply the force for moving the toggle linkage to operate the switch blade individual thereto at the pivoted connection between the toggle links at substantially right angles to the center line of the switch base individual thereto.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following detailed description, taken together with the accompanying drawings, in which:

45 Figure 1 is a view, in front elevation, of a typical installation of an operating mechanism for each of three switch units mounted on a suitable support for gang operation;

Figure 2 is a view, in side elevation, of the assembly illustrated in Figure 1;

Figure 3 is a view, in side elevation, of one of the switch units, the switch being shown in the closed position;

Figure 4 is a detail sectional view taken generally along the line 4—4 of Figure 3 and illustrating how the operating mechanism is intercon-

nected between the base and the rotatable insulator for operating the latter to swing the switch blade in the manner outlined hereinbefore and described in detail hereinafter;

Figure 5 is a view which illustrates diagrammatically the manner in which the toggle linkage performs its function in rotating the switch blade out of and into switch closed position; and

Figure 6 shows curves which demonstrate the relationship between the movement of one of the toggle links of the operating mechanism and the movement of the switch blade.

Referring now particularly to Figure 1 of the drawings, it will be observed that the reference character 10 designates, generally, a frame carrying cross beams 11 on which switch units, shown generally at 12, are mounted. It will be noted that three switch units 12 are illustrated, this being the arrangement which is used customarily for switching three phase alternating current circuits. The present invention is illustrated in conjunction with apparatus intended for use on circuits operating at voltages of the order of 23,000 volts and above. However, this is mentioned by way of illustration rather than limitation.

Each switch unit 12 includes a channel iron base 13 at the ends of which stationary insulators 14 are mounted. Intermediate the stationary insulators 14 is a rotatable insulator 15 the movement of which controls the operation of the switch unit 12. A toggle operating mechanism, shown generally at 16, is employed for rotating the insulator 15 to accomplish this function. The details of construction and manner of operation of the toggle operating mechanism 16 will be set forth hereinafter.

Since three switch units 12 are employed and it is desirable to operate them in unison, the toggle operating mechanisms 16 are interconnected by interphase rods 17. A rod 18 interconnects the toggle operating mechanism 16 of the left hand switch unit 12, as shown in Figure 1, and one arm of a bell crank 19 that is mounted on a suitable channel 20 which is carried by the cross beams 11. The other arm of the bell crank 19 is connected by a rod 21 to an operating handle 22 which is located in a position where it can be manually operated by a lineman. While the present invention is illustrated as being arranged for manual operation it will be understood that, if desired, suitable power driven mechanism can be employed in lieu of the manually operated handle 22.

As illustrated more clearly in Figure 3 the rotatable insulator 15 carries at its upper end a switch blade 26. Preferably the switch blade 26 is in the form of a tube of good conducting material such as copper and it is secured by a clamp 27 to the upper end of the rotatable insulator 15. At each end of the switch blade 26 there is provided a blade tip as set forth in detail in said Lindell application. The blade tip includes a main contact arm which is arranged to make contact engagement with a stationary main contact member that is illustrated, generally, at 30. It will be noted that the stationary main contact member 30 is mounted on a terminal bracket 31 which is secured to the upper end of each of the stationary insulators 14. Each terminal bracket 31 includes a terminal pad 32 formed integrally therewith to permit connection to the circuit associated therewith.

In order to avoid any arcing between the main contact arm and the contact fingers cooperating

therewith when the circuit therethrough is opened or closed, a load interrupter, shown generally at 42 is employed. The load interrupter 42 is carried by an angle bracket, mounted on the terminal bracket 31.

From the foregoing description it now will be apparent that the switch blade 26 in its movement from and to the switch closed position must perform mechanically certain functions which are widely different. When the main contact arm is moved out of or into contact engagement with the contact fingers, a relatively great force must be exerted. As previously indicated, this force must be increased under certain conditions. It is also desirable that the load interrupter be operated at a high speed. This is particularly desirable when the switch blade is moved toward the switch open position and an arc is drawn and must be extinguished within the load interrupter 42. Accordingly, the movement of the switch blade must be accelerated greatly during the portion of its movement where the contacts of the load interrupter are opened at high speed. After the current flow has been interrupted by the load interrupter 42, provision must be made for swinging the switch blade 26 to a position substantially at right angles to its switch closed position. The purpose of this is to provide maximum disconnect distance between the energized terminals of each of the switch units 12 when the switch is in the open position. However, this final movement of the switch blade 26 to the full open position can be at less mechanical advantage than is required for the operation thereof in disengaging or engaging the main contacts comprising the main contact arm 26 and the stationary main contact member 30 and for operating the load interrupter 42.

The toggle operating mechanism 16 associated with each of the rotatable insulators 15 permits the operation of each of the switch blades 26 in the manner described to accomplish these ends. This mechanism is illustrated in more detail in Figure 4 of the drawings. As there shown each of the rotatable insulators 15 is provided at its base with an arm 79. In Figure 4 the arm 79 is shown in the position which it occupies when the associated switch blade 26 is in the switch closed position. The toggle operating mechanism 16 is arranged to swing the arm 79 and therewith the insulator 15 and switch blade 26 in a clockwise direction through an arc of ninety degrees. For this purpose the arm 79 is pivotally connected at 80 near its outer end to a relatively short toggle link 81, which, in turn, is pivotally connected at 82 to a relatively long toggle link 83. The latter toggle link is mounted to operate about a fixed pivot 84 on the base 13.

For illustrative purposes it is pointed out that in one concrete embodiment of the invention the stationary insulators 14 were located on thirty-eight inch centers with the rotatable insulator 15 located midway therebetween. The arm 79 had an effective length from the center 85 of rotation of the insulator 15 to the pivot point 80 of seven inches. The distance between the pivot points 80 and 82 was five inches while the distance between the pivot points 82 and 84 was eight inches. The pivot point 84 was located on a circle whose radius was fourteen inches and whose center coincided with the center 85 of rotation of the insulator 15. Further the pivot point 84 was offset from a line, represented by the broken line 86, through the centers of the insulators 14 and 15 by one and five-eighths

inches. It will be understood that the line 86 is in the plane which is normal to the base 13 and includes the longitudinal axis of the switch blade 26 when it is in the switch closed position. The pivot point 84 is located on the side of the line 86 toward the direction in which the switch blade 26 swings toward the open circuit position. The purpose of offsetting the pivot point 84 in this manner is to reduce to a minimum the sidewise movement of the interphase rods 17 as they move generally longitudinally to and from the switch closed position.

It is desirable to lock each of the switch blades 26 in the switch closed position. One reason for this is to avoid accidental opening of the switch units 12 in the event that exceedingly heavy current flow takes place therethrough and magnetic reactions are developed which tend to swing the switch blades 26 to the open position. For this purpose the toggle operating mechanism 16 is constructed so that the links 81 and 83 thereof can swing slightly past a position where they are in end-to-end centered relation. A stop 87 is carried by each of the bases 13 and is located in the path of the relatively long toggle link 83 so as to limit the movement thereof past the center position. At the same time, because the toggle links 81 and 83, as shown in Figure 4, are in the over center position and react against the stop 87, any force tending to rotate the insulator 15 or the switch blade 25 carried thereby is prevented from effecting such rotation because of the over center locked position of the toggle links 81 and 83.

Since the toggle operating mechanism 16 swings past the centered position when the switch is closed, the adjustment of the various pivot points is made non-critical and the mechanism can be factory assembled for simplified field erection. Also this arrangement permits all of the joints of the operating mechanism to be broken loose before any movement of the switch blade takes place. This feature is particularly advantageous under conditions of corrosion, sleet and ice.

While the arrangement of the arms 79 and the toggle links 81 and 83 is such that the switch blade 26 of each switch unit 12 is operated only to the full open position which is ninety degrees away from the switch closed position, it is desirable to reduce the shock incident to the swinging of each of the switch blades 16 to the open position. For this purpose a resilient bumper 91, preferably formed of rubber, is mounted on a bracket 92 that is carried by the base 13. The bumper 91 is located in the path of movement of the arm 79 and is arranged to be engaged thereby when it approaches the position corresponding to the full open position of the switch blade. The bumper 91 also prevents the arm 79 and link 81 from moving into toggle locking positions.

The operation of each of the switch units 12 is accomplished by rocking the relatively long toggle link 83 away from the stop 87 in a counter-clockwise direction. This is accomplished preferably by connecting the operating mechanism to the pivotal connection 82 between the toggle links 81 and 83. The only force then acting on the pivot 84 is that which is transmitted thereto along the link 83. As shown in Figure 4 this is accomplished through the provision of coupling members 93 and 94. It will be understood that they are arranged to be connected to the rods 17

and 18, previously referred to, for simultaneous gang operation of the switch units 12.

In describing the functioning of the toggle operating mechanism 16, reference may be had to the diagrammatic illustration in Figure 5. The pivot point 82, when it is located at A, corresponds to the position shown in Figure 4 where the toggle links 81 and 83 are in the over center toggle locked position against the stop 87. When the toggle link 83 is swung through an angle of a few degrees, the pivot point 82 is swung to the position B where the toggle links 81 and 83 are in end-to-end centered relationship. During this movement from A to B substantially no movement of the pivot point 82 takes place because of lost motion in the pivotal connections. There is then no change in the position of the main contact arm 28 with respect to the stationary main contact member 30.

As the toggle link 83 is rocked in the counter-clockwise direction so as to shift the pivot point 82 from the position B, this pivot point follows along the arc 95. This is accompanied by movement of the pivot point 80 at the outer end of the arm 79 along the arc 96. When the pivot point 80 is swung to the position C and the pivot point 82 occupies the position D, the switch blade 26 has been swung through ninety degrees from the switch closed to the switch open position. A reversal of this movement caused by a rocking of the toggle link 83 in a clockwise direction causes the pivot point 80 to swing along the arc 96 back to its initial position corresponding to the switch closed position.

The relationship between the movement of the toggle link 83 and the corresponding movement of the switch blade 26 is illustrated by the curve 97 in Figure 6 of the drawings. It will be observed that this curve is plotted with movement of the toggle link 83 as abscissas and movement of the switch blade 26 away from the closed position as ordinates. The curve 99 is drawn for comparison to illustrate what the straight line relationship would be if the movement of the switch blade 26 corresponded exactly to the movement of the toggle link 83.

Particularly with reference to the curve 97 and to the initial portion 99 thereof, it will be noted that during the initial opening movement of the toggle link 83 through a considerable extent there is only a slight movement of the switch blade 26 to effect the separation of the main contact arm from the stationary main contact 30 at each end. This mechanical advantage relationship then provides the necessary force required to overcome the biasing action of the contact fingers on the main contact arms and to overcome conditions of corrosion, sleet and ice without requiring that undue force be applied to the toggle link 83 by the operating mechanism, such as the manually-operable handle 22.

As illustrated at the portion 100 of the curve 97 the movement of the switch blade 26 is accelerated with respect to the movement of operating mechanism for the load interrupter 42 for moving the movable contact thereof toward the open position at a relatively high speed for interrupting the circuit and drawing an arc within the load interrupter 42.

The curve 97 shows that, after the switch blade 26 has effected the operation of the load interrupter 42, its movement approximates that of the toggle link 83 during the remainder of the movement of the switch blade 26 to the switch open position.

When the switch blade 26 is swung to the

switch closed position this sequence of movement is reversed. That is, when the switch blade 26 swings past the load interrupter 42 at each end, it effects the operation of its contacts to close the circuit at an accelerated speed as compared to the speed of swinging movement of the link 83. Then, when the main contact arm 29 engages the contact fingers and a relatively great force is required for completing the closing action of the switch, the toggle link 83 swings through a relatively large arc while the switch blade 26 is completing its travel and swinging through a relatively small arc with a corresponding multiplication in the force applied by the toggle link 83 received from the operating mechanism at the pivot point 82.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. Mechanism for operating a switch blade carried by and movable with an insulator rotatably mounted on a base carrying in spaced relation a stationary insulator on which are mounted main contacts requiring relatively great force for disengagement and engagement by said switch blade and a load interrupter requiring relatively high speed operation by movement of said switch blade following such disengagement and prior to such engagement comprising, in combination, an arm rigidly attached to said rotatable insulator, a relatively short toggle link pivoted at one end to said arm, a relatively long toggle link pivoted at one end to the other end of said relatively short toggle link and at the other end pivoted to said base at a point offset on the side toward opening movement of said switch blade from a plane perpendicular to said base and containing the longitudinal axis of said switch blade in switch closed position, said toggle links being in end-to-end centered position when said switch blade is in closed position and movable slightly past said centered position to lock said switch blade in closed position, stop means for limiting the movement of said toggle links past center position, and driving means connected to the pivotal connection between said toggle links for moving them to swing said switch blade from and to its locked switch closed position to and from its switch open position.

2. Mechanism for operating a switch blade carried by and movable with an insulator rotatably mounted on a base carrying in spaced relation a stationary insulator on which are mounted main contacts requiring relatively great force for disengagement and engagement by said switch blade and a load interrupter requiring relatively high speed operation by movement of said switch blade following such disengagement and prior to such engagement comprising, in combination, an arm rigidly attached to said rotatable insulator, a relatively short toggle link pivoted at one end to said arm, a relatively long toggle link pivoted at one end to the other end of said relatively short toggle link and at the other end pivoted to said base at a point offset on the side toward opening movement of said switch blade from a plane perpendicular to said base and containing the longitudinal axis of said switch blade in switch closed position, said toggle links being in

end-to-end centered position when said switch blade is in closed position, and driving means connected to the pivotal connection between said toggle links for moving them to swing said switch blade from and to its switch closed position to and from its switch open position.

3. Mechanism for operating a switch blade carried by and movable with an insulator rotatably mounted on a base carrying in spaced relation a stationary insulator on which are mounted main contacts requiring relatively great force for disengagement and engagement by said switch blade and a load interrupter requiring relatively high speed operation by movement of said switch blade following such disengagement and prior to such engagement comprising, in combination, an arm rigidly attached to said rotatable insulator, a relatively short toggle link pivoted at one end to said arm, a relatively long toggle link pivoted at one end to the other end of said relatively short toggle link and at the other end pivoted to said base at a point offset on the side toward opening movement of said switch blade from a plane perpendicular to said base and containing the longitudinal axis of said switch blade in switch closed position, said toggle links being in end-to-end centered position when said switch blade is in closed position, and driving means connected to the pivotal connection between said toggle links to move the pivotal connection therebetween through a relatively great distance while said switch blade is being swung through a relatively short distance from and to its switch closed position and to accelerate the movement of said switch blade over the movement of said pivotal connection while said switch blade is operating said load interrupter.

4. Mechanism for operating a switch blade carried by and movable with an insulator rotatably mounted on a base carrying in spaced relation a stationary insulator on which are mounted main contacts requiring relatively great force for disengagement and engagement by said switch blade and a load interrupter requiring relatively high speed operation by movement of said switch blade following such disengagement and prior to such engagement comprising, in combination, an arm rigidly attached to said rotatable insulator, a relatively short toggle link pivoted at one end to said arm, a relatively long toggle link pivoted at one end to the other end of said relatively short toggle link and at the other end pivoted to said base at a point offset on the side toward opening movement of said switch blade from a plane perpendicular to said base and containing the longitudinal axis of said switch blade in switch closed position, said toggle links being in end-to-end centered position when said switch blade is in closed position and movable slightly past said centered position to lock said switch blade in closed position, stop means for limiting the movement of said toggle links past their center position, and driving means connected to the pivotal connection between said toggle links to move the pivotal connection therebetween through a relatively great distance while said switch blade is being swung through a relatively short distance from and to its switch closed position and to accelerate the movement of said switch blade over the movement of said pivotal connection while said switch blade is operating said load interrupter.

5. Mechanism for operating a switch blade carried by and movable with an insulator rotatably mounted on a base carrying in spaced rela-

tion a stationary insulator on which are mounted main contacts requiring relatively great force for disengagement and engagement by said switch blade and a load interrupter requiring relatively high speed operation by movement of said switch blade following such disengagement and prior to such engagement comprising, in combination, an arm rigidly attached to said rotatable insulator, a relatively short toggle link pivoted at one end to said arm, a relatively long toggle link pivoted at one end to the other end of said relatively short toggle link and at the other end pivoted to said base at a point offset on the side toward opening movement of said switch blade from a plane perpendicular to said base and containing the longitudinal axis of said switch blade in switch closed position, said toggle links being in end-to-end centered position when said switch blade is in closed position and movable slightly past said centered position to lock said switch blade in closed position, a stop carried by said base and cooperating with said relatively long toggle link to limit the movement of said toggle links past their center position, and driving means connected to the pivotal connection between said toggle links for moving them to swing said switch blade from and to its locked switch closed position to and from its switch open position.

6. Mechanism for operating a switch blade carried by and movable with an insulator rotatably mounted on a base midway between two stationary insulators carried thereby on each of which are mounted main contacts requiring relatively great force for disengagement and engagement by said switch blade and a load interrupter requiring relatively high speed operation by movement of said switch blade following such disengagement and prior to such engagement comprising, in combination, an arm rigidly attached to said rotatable insulator, a relatively short toggle link pivoted at one end to said arm, a relatively long toggle link pivoted at one end to the other end of said relatively short toggle link and at the other end pivoted to said base at a point offset on the side toward opening movement of said switch blade from a plane perpendicular to said base and containing the longitudinal axis of said switch blade in switch closed position, said toggle links being in end-to-end centered position when said switch blade is in closed position and movable slightly past said centered position to lock said switch blade in closed position, stop means carried by said base and cooperating with said toggle links to limit the movement thereof past their center position, and driving means connected to the pivotal connection between said toggle links for moving them to swing said switch blade from and to its locked switch closed position to and from its switch open position.

7. Mechanism for operating a switch blade carried by and movable with an insulator rotatably mounted on a base midway between two stationary insulators carried thereby on each of which are mounted main contacts requiring relatively great force for disengagement and engagement by said switch blade and a load interrupter requiring relatively high speed operation by movement of said switch blade following such disengagement and prior to such engagement comprising, in combination, an arm rigidly attached to said rotatable insulator, a relatively short toggle link pivoted at one end to said arm, a relatively long toggle link pivoted at one end

to the other end of said relatively short toggle link and at the other end pivoted to said base at a point offset on the side toward opening movement of said switch blade from a plane perpendicular to said base and containing the longitudinal axis of said switch blade in switch closed position, said toggle links being in end-to-end centered position when said switch blade is in closed position, and driving means connected to the pivotal connection between said toggle links to move the pivotal connection therebetween through a relatively great distance while said switch blade is being swung through a relatively short distance from and to its switch closed position and to accelerate the movement of said switch blade over the movement of said pivotal connection while said switch blade is operating said load interrupters.

8. Mechanism for operating simultaneously a plurality of spaced apart switch blades each carried by and movable with an insulator rotatably mounted on a base carrying in spaced relation a stationary insulator on which are mounted main contacts requiring relatively great force for disengagement and engagement by the respective switch blade and a load interrupter requiring relatively high speed operation by movement of the respective switch blade following such disengagement and prior to such engagement comprising, in combination, an arm rigidly attached to each rotatable insulator, a relatively short toggle link pivoted at one end to each of said arms, a relatively long toggle link pivoted at one end to the other end of each of said relatively short toggle links and at the other end to the respective base at a point offset on the side toward opening movement of the respective switch blade from a plane perpendicular to the respective base and containing the longitudinal axis of the respective switch blade in switch closed position, the toggle links of each set being in end-to-end centered position when the respective switch blade is in closed position and movable slightly past said centered position to lock the respective switch blade in closed position, stop means carried by each base and cooperating with the respective set of toggle links to limit the movement thereof past their center position, and driving means commonly connected to the pivotal connection between the toggle links of each set for moving them to swing the respective switch blades from and to their locked switch closed positions to and from their switch open positions.

9. Mechanism for operating simultaneously a plurality of spaced apart switch blades each carried by and movable with an insulator rotatably mounted on a base carrying in spaced relation a stationary insulator on which are mounted main contacts requiring relatively great force for disengagement and engagement by the respective switch blade and a load interrupter requiring relatively high speed operation by movement of the respective switch blade following such disengagement and prior to such engagement comprising, in combination, an arm rigidly attached to each rotatable insulator, a relatively short toggle link pivoted at one end to each of said arms, a relatively long toggle link pivoted at one end to the other end of each of said relatively short toggle links and at the other end to the respective base at a point offset on the side toward opening movement of the respective switch blade from a plane perpendicular to the respective base and containing the longitudinal axis of the respective switch blade in a

switch closed position, each set of toggle links being in end-to-end centered position when the respective switch blade is in closed position, and driving means commonly connected to said sets of toggle links at the pivotal connections therebetween to move conjointly the pivotal connections between the links of each set through a relatively great distance while the corresponding switch blade is being swung through a relatively short distance from and to its switch closed position and to accelerate the movement of each switch blade over the movement of the pivotal
